UNITED STATES PATENT OFFICE.

AUGUST G. SANDMAN, OF ST. DENIS, MARYLAND.

CAR-BRAKE.

SPECIFICATION forming part of Letters Patent No. 769,358, dated September 6, 1904.

Application filed March 9, 1896. Serial No. 582,355. (No model.)

To all whom it may concern:

Be it known that I, AUGUST G. SANDMAN, a citizen of the United States, residing at St. Denis, Baltimore county, State of Maryland, have invented certain new and useful Improvements in Car-Brakes, of which the following, taken in connection with the accompanying drawings, is a specification sufficiently full, clear, and accurate as will enable those skilled in the art to embody and use the same.

The main object of my invention is the production of an air-brake and a hand-brake, first, each of which can be used independently of the other; second, both of which can be used simultaneously, and, third, the hand-brake adapted to supplement the air-brake and also to hold the shoes against the wheels at either or both ends of the car when the air-brake mechanism is in a partly or wholly released position.

With this object in view my invention consists in certain novelties of construction and combinations of elements hereinafter described, and pointed out in the claims.

The improvements are adapted for application to passenger and freight cars having either four or six wheel trucks and where the shoes are applied to one side only or to both sides of each wheel. The rigging on the truck operated by the upper brake-lever-connecting rod may be of any suitable construction, as the particular variety is not of the essence of my invention.

On the drawings, by way of example, I have illustrated one embodiment of my invention, the best mode I have so far devised, with the shoes applied to one side only of the wheels of four and six wheel trucks.

Figure 1 is an upper plan view showing both the hand and air brakes in operative positions, the dotted lines indicating the outlines of a passenger-car body. Fig. 2 is a side view of Fig. 1. Fig. 3 is a detail view of the connection of the hand and air brake mechanisms to the upper brake-lever-connecting rods.

Fig. 4 is a modification of the construction shown in Fig. 3. Fig. 5 is a detail view of a Hodge non-floating lever and lever-connect-

ing rod. Figs. 6 and 7 are plan and side views of my improvements applied to a car having 50 six-wheel trucks.

The letter A designates an air-brake cylinder and piston of the usual construction.

B B are the cylinder-levers.

C is a cylinder-lever tie-rod. 55
E E are Hodge non-floating levers; D D, Hodge lever-connecting rods, each having a slot I at one end and journaled to levers E E by pivot-pins H, as indicated in Fig. 5.

F F are brackets attached to the under side 60 of the car and to which are pivoted one end of each of the levers E E, as shown, or in any other desirable way, and G G are upper brake-lever-connecting rods. The foregoing enumerated parts or their equivalents 65 constitute the necessary elements of the air-brake mechanism exclusive of the attachments on the trucks.

For the purpose of operating the rods G and applying the brake-shoes at each end of the 70 car independently of the action of the air-brake cylinder and piston I join the hand-brake-connecting rods P P to the upper brake-lever-connecting rods G G (see Fig. 3) or to the lever E (see Fig. 6) through the medium of floating levers R R and yielding elements S or S'. Fig. 3 shows the elements S as a chain, and Fig. 4 the element S' as a slotted bar, one being considered the equivalent of the other.

A floating connecting-rod T unites the two 80 floating levers R. R. The ordinary hand-wheels and chains attached to rods P P are used on the platforms, as shown at the extreme ends of Figs. 1 and 6, and need not be described. The ordinary means for pivoting 85 one element to another is also employed, the length of the levers severally adapted to the particular location, and the length of the arms thereof proportionate to the force with which the brake-shoes are to be applied to the wheels. 90

The *modus operandi* is as follows: When the engineer shifts the handle of the engineer's valve, allowing air to escape to the atmosphere from the train-pipe, air from the auxiliary reservoir passes to the cylinder A 95 and moves the piston and applies the brakes.

As the ends of the levers E E are pivoted in the brackets F F and as there is a flexible or compensating means uniting levers R to rods G or levers R to levers E the operation does not in any way affect the hand-brake mechanism. When the shaft of the hand-brake is revolved in the usual manner, the levers R are rotated about the pivotal points, where they are attached to the rod T, the chains drawn taut, and then the rods G are advanced and the brake-shoes brought in contact with the wheels.

It is obvious from the foregoing that the air-brake can be used independently and likewise simultaneously or in unison with the hand-brake, also that the hand-brake can be applied as supplemental to the air-brake when descending steep grades or at other times. Under the latter condition the hand-brake is capable of performing a very important function, for should the air partially or wholly escape or leak from the cylinder A and the piston move to a released position the hand-brake would still hold the brake-shoes against the wheels. Moreover, it often happens that cars equipped with the ordinary air and hand brakes are left on inclined tracks or grade-sidings with both the air and hand brakes set. When air leaks from the cylinder, the piston travels, the brakes release, and the car under the action of gravity moves from its proper location. My improvements prevent such release when the hand-brake is set, for the leakage from the air-cylinder and the partial or entire release of the air-brake does not impair the efficiency of the hand-brake.

To allow of the independent application of the hand-brake when the air-brake is in a released position, I have introduced the novel features hereinbefore described—to wit, the chain or slotted bar, as shown in Figs. 3, 4, and 6, and the slotted Hodge lever-connecting rods. (Shown in Fig. 5.) When the hand-wheel is turned and the lever R rotated, the lever E is advanced in the direction of the cylinder A. The slots in the rods D or equivalent means allow such movement without moving the rods D themselves and the piston inasmuch as the pivot-pins travel in the slots. In an analogous manner, as stated, by the use of the chain S or slotted bar S' the action of the air-brake does not impart motion to the hand-brake mechanism.

While I have shown and described but one complete example of the physical embodiment of my invention and applied to trucks with four and six wheels, which constitutes the best mode so far devised, and one modification of the yielding connection, I do not thereby intend to exclude other and equivalent modes inasmuch as many changes may be introduced in the way of construction and arrangement which will fall within the scope of my invention.

Moreover, parts of my invention may be used without the appropriation of the entire mechanism. For instance, the rod T may be omitted and the hand-brakes operated independently on each or either end of the car. Again, the chain S may be attached directly to the end of lever E for the operation of the rod G, as in Fig. 6, and a flexible connection employed to perform the function of the slot I at the end of the rod D. Still further, in place of the yielding connection between rods D and lever E, I may substitute a yielding connection between the end of rod D and lever B or between rod C and lever B or slot the piston-stem, &c., or in Fig. 1 rod G may be slotted and advanced without imparting motion to lever E and the air-brake mechanism S, being attached to G. The yielding element S or S' may also be differently located. Such and all similar changes I shall regard as immaterial variations or modifications when used as substitutions for my construction or purposes.

What I claim as new, and desire to secure by Letters Patent, is—

1. A combined air-brake and hand-brake mechanism consisting of the air-cylinder and piston; cylinder-levers; cylinder-lever tie-rod; rods D, D; levers E, E; brake-lever-connecting rods G, G, for applying the shoes; hand-brake rods P, P; levers R, R; rod T; and yielding means between the end of a lever R and a rod G.

2. A combined air-brake and hand-brake mechanism consisting of an air-brake cylinder and piston; cylinder-levers; cylinder-lever tie-rod; rods D, D; levers E, E; rods G, G, for applying the shoes; hand-brake rods; levers R, R; and rod T; the end of a lever R being in operative connection with a rod G by means of a chain S, and the end of a rod D being connected to a lever E by a slot-and-pin mechanism.

3. A combined air-brake and hand-brake mechanism consisting of an air-brake cylinder and piston; cylinder-levers; cylinder-lever tie-rod; rods D, D; levers E, E; rods G, G, for applying the shoes; hand-brake rods; levers R, R; and rod T; the ends of levers R, R, being in operative connection with rods G, G by means of chains S, S, and the ends of rods D, D, each being connected to a lever E by a slot-and-pin mechanism.

4. The combination in a brake mechanism, of two non-floating levers; rods for applying the shoes to the wheels; a pneumatically-actuated system of levers in connection with said non-floating levers; two hand-brake rods; two floating levers; means for uniting the floating levers; means connecting the floating levers and the rods for applying the shoes; and a yielding joint between the rods for applying the shoes and the hand-actuated system.

5. The combination in a brake mechanism, of two non-floating levers; rods for applying the shoes to the wheels; a pneumatically-actuated system of levers in connection with said 5 non-floating levers; a yielding joint between the non-floating levers; a hand-actuated lever system in connection with the rods for ap-

plying the shoes; and a yielding joint between the rods for applying the shoes and the hand-actuated system which unites the two rods. 10
